UNITED STATES PATENT OFFICE.

BIRNEY C. BATCHELLER, OF PHILADELPHIA, PENNSYLVANIA, ASSIGNOR
TO THE PEARSALL PNEUMATIC TUBE AND POWER COMPANY, OF NEW
YORK, N. Y., A CORPORATION OF NEW YORK.

PNEUMATIC-TUBE SYSTEM.

No. 840,194.

Specification of Letters Patent.

Patented Jan. 1, 1907.

Application filed May 1, 1905. Serial No. 258,290.

To all whom it may concern:

Be it known that I, BIRNEY C. BATCHELLER, a citizen of the United States of America, residing in the city and county of Philadelphia, in the State of Pennsylvania, have invented a certain new and useful Improvement in Pneumatic-Tube Systems, of which the following is a true and exact description, reference being had to the accompanying drawings, which form a part thereof.

My invention relates to an improved pneumatic-tube system adapted to operate both as a pressure and vacuum system, the object of my invention being to provide for the operation of the system from one station as a pressure system and from a connected station as a vacuum system, also to provide improved mechanism for the operation and regulation of the system as a whole.

20 Broadly speaking, my invention consists in providing a system of the kind indicated with means for actuating it as a pressure system at one station and with means for actuating it as a vacuum system controlled and operated from the other connected station.

The nature of my improvements as a whole will be best understood as described in connection with the drawings, in which they are illustrated, and in which—

30 Figure 1 is a side elevation indicating the general character of the system. Fig. 2 is a front view of the valves and valve-actuating mechanism at the home station, shown on the section-line 2 2 of Fig. 5. Fig. 3 is a side elevation of the same appliances, shown on the section-line 3 3 of Fig. 5. Fig. 4 is a cross-sectional view on the line 4 4 of Fig. 2; and Fig. 5, a plan view, partly sectioned, on the line 5 5 of Fig. 2.

40 A and B indicate two connected stations, C being the pneumatic tube connecting said stations. The end C' of the tube at station A, or the home station, is indicated as beveled to afford a seat for the flap-valve, (indicated at D,) D' indicating the hinge-arms to which the valve is attached, while the end C' at station B is normally open. The tube C at the home station connects, through lateral ports C³, with a chamber H' of a casing H, which is 45 formed with a diaphragm-chamber H² at its top and which is in communication with the upper end of a vacuum pipe or reservoir G. The valve H' normally closes the mouth of

the vacuum-pipe and is connected, through a spindle H⁴, with the diaphragm H⁵, which 55 extends across the diaphragm-chamber H² and is drawn upwardly a spring H⁶, fastened to a bracket H⁷. The vacuum-chamber H² connects, through a port H⁸, (see Fig. 2,) with a chamber I² of a casing I, the lower portion 60 of which connects, through a pipe I', with a vacuum-reservoir (not shown) and through a port I³ with the atmosphere.

I⁵ is a valve which when drawn up closes the port I³ and when allowed to fall closes 65 the vacuum-pipe I', and I⁴ indicates an electromagnet acting on the valve is an armature and connected with the circuit-wires P P; which wires extend to the station B and are there connected with spring-terminals P' 70 P', normally connected by a plate Q, drawn toward and held in contact with the spring-terminals by a time escapement device, (indicated at O,) the contact-plate being drawn up and the time escapement set in operation 75 through a lever Q² and chain Q'.

The electromagnetic mechanism shown and the general system of which it forms a part form the subject-matter of my copending applications for Letters Patent, Serial 80 No. 251,208, filed March 21, 1905, and Serial No. 249,569, filed March 11, 1905, and are therefore not specifically claimed in the present application.

At the home station the tube is also connected, through lateral passages, (indicated at C⁴,) with a chamber F² of a casing F, said casing having also a chamber F', which is in constant communication with a pressure or supply pipe E, the chambers F' and F² communicating through the valve-seated port F³. The valve F' normally closes this port, being held to its seat by a spring F⁴, and the valve is provided with a spindle F⁵, which projects up through the casing and through 95 which the valve is opened.

J' is a hand-lever pivoted on or to the shaft J and having a lever extension J², which connects, through a pin J³, with the slotted head N of the time escapement mechanism to be 100 described. The lever or its arm J² has also attached to it the laterally-extending arm J⁴, placed to contact with a finger or arm K' of a lever-arm K, which is pivoted on the shaft J, and connected at its outer end with a link K², 105 which in turn is pivotally connected to a le-

ver-arm L, pivoted on an extension of the pivot-pin D² of the flap-valve D and having connected to it the locking-lever L'.

M is a latch adapted to engage the end of the lever-arm K when it is turned down to a horizontal position, the latch being pivoted at M' and having a laterally-extending arm M², which is connected to a rod M³, having a laterally-extending finger M⁴ arranged in the path of the shoulder N', M⁵ being a spring which tends to draw up the rod M³ and to hold the latch-lever M in engaged position.

The slotted head N, having the shoulder N' at its bottom, is attached to the upper end of the piston-rod N², the piston N³ moving in the time escapement cylinder O and being pressed downward by a spring O'. The cylinder O has a lower port O' connecting, through a lateral passage O⁴, with an intermediate port O², closed by a spring-valve O⁵, and with an upper restricted port O³, the orifice of which is regulated by an adjusting-needle O⁶.

It will be understood that in a system of this kind the end of the tube at the home station must be normally closed against the passage of either compressed air or air at atmospheric pressure. This may be accomplished in many ways; but it is simply and efficiently accomplished by the provision of the flap-valve D, normally held to its seat by light spring-pressure, such a spring being indicated, for instance, at D³, Fig. 5, while a locking-lever L' is provided to hold the valve D positively closed at certain times, D⁴ in the same figure indicating a spring which normally holds the locking-lever L' in non-operative or retracted position, as shown in Fig. 3. When it is desired to send a carrier from the home station to the outer station B, the operator raises the flap-valve D and inserts the carrier into the end of the tube, the valve closing after the insertion. The operator then turns the lever J' toward the left, the arm J⁴ impinging against the finger K' of the lever K and turning this lever downward and through the link K² and connected arm L turning the locking-lever L' down on the flap-valve D, the motion being comparatively rapid at the beginning and as the lever-arm K and link K² approach parallelism the force being greatly increased, so that finally the flap-valve is held positively locked to its seat. The downward motion of the lever-arm K brings it finally into contact with the valve-spindle F⁶, opening the pressure-valve F⁶, and at the end of its movement the lever K is engaged in practically horizontal position by the latch-lever M. The described movement of the lever-arm J' also effects a lifting movement of its connected arm J², which draws up the piston of the time escapement device, the fluid in the top of the cylinder O escaping freely through the spring-valve O⁵, and when the air-valve has

been latched open the arm J' can be turned back to normal non-operative position without affecting any of the parts which it has moved in its working stroke. The admission of compressed air by the opening of the valve F⁶ propels the carrier to the out station, and of course the time escapement device is operating, the piston N³ moving downward while the carrier travels, the fluid in the bottom of the cylinder O escaping gradually upward through the restricted port O³ until finally the shoulder N' of the piston-rod comes in contact with the finger M⁴ of the rod M³, drawing it downward and throwing the latch-lever M out of engagement with the end of the lever K, whereupon the valve F⁶ closes and the locking-lever L' moves out to its normal non-operative position.

When it is desired to send a carrier from the out station to the home station, the operator at the out station inserts the carrier in the end C² of the tube and then turns the lever Q², setting the time-escapement O at the out station and through the plate Q opening the circuit through the wires P P, with the result that the electromagnet I⁴ is deenergized and the valve I⁵ moves downward, opening the port I³ and closing the vacuum-pipe I'. This permits atmospheric air to enter through the port I³, chamber I², and port H⁸ into the diaphragm-chamber H², whereupon the spring H⁶ raises the diaphragm H⁵, and the connected vacuum-valve H³, the vacuum communicating, through the ports C³, with the tube and causing the flow of air from the out station to the in station, with consequent transmission of the carrier, which on arrival at the home station impinges against and opens the flap-valve D, the time escapement at the out station in the meanwhile gradually bringing the circuit-closing plate to operative position in contact with the spring-terminals P', the contact restoring the current through the wires P P and energizing the magnet I⁴, so that the valve I⁵ is drawn up, closing the port I³, opening the vacuum-pipe I', drawing down the diaphragm, and closing the valve H³. The air is admitted to the chamber H² by the opening of the flap-valve D and of course aids in closing the vacuum-valve.

The specific mechanism shown is well adapted for the purposes had in view and described, but is not essential to the broad utilization of my invention, and I therefore do not wish to be understood as in any way limiting my claims on such specification except where it is especially and clearly referred to in the claims as limiting elements therein.

Having now described my invention, what I claim as new, and desire to secure by Letters Patent, is—

1. A pneumatic-tube system comprising a transmission-tube, in combination with com-

pressed-air and vacuum supply chambers connected to one end of said tube, normally closed valves for controlling the connection of said supply-chambers with the tube, 5 means for closing the end of the tube which is connected with the supply-chamber to the passage of outer air, means for opening the compressed-air-supply valve situated and actuated at the end of the tube which is connected with the supply-chambers and means 10 for opening the vacuum-supply valve having actuating means located at the other end of the tube.

2. A pneumatic-tube system comprising a transmission-tube, in combination with compressed-air and vacuum supply chambers connected to one end of said tube, normally closed valves for controlling the connection of said supply-chambers with the tube, 15 means for closing the end of the tube which is connected with the supply-chamber to the passage of outer air, means for opening the compressed-air-supply valve situated and actuated at the end of the tube which is connected with the supply-chambers, means for 20 opening the vacuum-supply valve having actuating means located at the other end of the tube, and means for closing the open supply-valves after a carrier has passed through the 25 tube.

3. A pneumatic-tube system comprising a transmission-tube, in combination with compressed-air and vacuum supply chambers connected to one end of said tube, normally closed valves for controlling the connection of said supply-chambers with the tube, means for closing the end of the tube which is connected with the supply-chamber to the 30 passage of outer air, means for opening the compressed-air-supply valve situated and actuated at the end of the tube which is connected with the supply-chambers, means for 35 opening the vacuum-supply valve having actuating means located at the other end of the tube and time escapement means for closing the open supply-valves set in operation by the means employed to open said valves.

4. In a pneumatic-tube system adapted to 40 operate both as a pressure and vacuum sys-

tem and having pressure and vacuum supply chambers connected to one end thereof, the combination therewith of normally closed valves controlling the pressure and vacuum connections, a flap-valve D, at the end of the 45 tube, normally held closed by resilient means, means located and actuated at the valved end of the tube for opening the pressure-supply valve and locking the flap-valve and means for opening the vacuum-valve actuated from the other end of the tube.

5. A pneumatic-tube system comprising a transmission-tube, in combination with compressed-air and vacuum supply chambers connected to one end of said tube, normally closed valves for controlling the connection of said supply-chambers with the tube, a gate-valve at the end of the tube which is connected with the supply-chambers, means for 50 opening the compressed-air-supply valve and 55 for locking the gate-valve situated and actuated at the end of the tube which is connected with the supply-chambers and means for opening the vacuum-supply valve having 60 actuating means located at the other end of the tube.

6. In a pneumatic-tube system adapted to operate both as a pressure and vacuum system and having pressure and vacuum supply chambers connected to one end thereof, the 65 combination therewith of normally closed valves controlling the pressure and vacuum connections, a flap-valve D, at the end of the tube normally held closed by resilient means, a pivoted lever K, arranged when actuated 70 to open the pressure-valve after moving through a determined angle, a flap-valve locking-lever L', having a lever-arm L, extending from it, a link K', connecting arm L, and lever K, as described, a latch for holding 75 lever K, and connected parts in position to keep the pressure-valve open, a time escapement device for releasing the latch and manually-operated means for actuating lever K, and setting the time escapement in operation.
